UNITED STATES PATENT OFFICE.

MARX GARLIC, OF PHILADELPHIA, PENNSYLVANIA.

DESIGN FOR A TRAY FOR BICYCLE-CASES.

SPECIFICATION forming part of Design No. 24,488, dated July 16, 1895.

Application filed October 30, 1894. Serial No. 527,489. Term of patent 14 years.

To all whom it may concern:

Be it known that I, MARX GARLIC, a citizen of the United States, residing in the city and county of Philadelphia, State of Pennsylvania, have invented and produced a new and original Design for Trays for Bicycle or Tricycle Cases, of which the following is a specification, reference being had to the accompanying drawing, forming part thereof.

The leading feature of my design for a tray for a bicycle or tricycle case is a body closed on one side, open on the other side, and of the form of a scalene triangle truncated at one end.

The figure represents a perspective view of a tray embodying my design.

In the drawing, A designates the body of a tray, the same having one side B closed and the opposite side C open. In the open side are longitudinal slats D and transverse straps 20 E. The body is of the form of a scalene triangle truncated at the end F.

What I claim is—

The design for a tray of a bicycle or tricycle case, substantially as shown and described. 25

MARX GARLIC.
